(57) **CLAIM**

The ornamental design for an eyelet interference screw, as shown and described.

DESCRIPTION

FIG. 1 is a perspective view of an eyelet interference screw according to my design, which comprises of an eyelet and an interference screw;

FIG. 2 is a front view of the eyelet interference screw according to my design;

FIG. 3 is a right side view of the eyelet interference screw according to my design;

FIG. 4 is a rear view of the eyelet interference screw according to my design;

FIG. 5 is a left side view of the eyelet interference screw according to my design;

FIG. 6 is an enlarged bottom view of the eyelet interference screw according to design;

FIG. 7 is an enlarged top view of the eyelet interference screw according to my design;

FIG. 8 is a perspective view of the interference screw portion of FIG. 1, which is shown with the eyelet portion removed for ease of illustration;

FIG. 9 is a front view of FIG. 8;

FIG. 10 is a right side view of FIG. 8;

FIG. 11 is a rear view of FIG. 8;

FIG. 12 is a left side view of FIG. 8;

FIG. 13 is an enlarged top view of FIG. 8;

FIG. 14 is an enlarged bottom view of FIG. 8;

FIG. 15 is a perspective view of the eyelet portion of FIG. 1, which is shown with the interference screw portion removed for ease of illustration;

FIG. 16 is a front view of FIG. 15;

FIG. 17 is a right side view of FIG. 15;

FIG. 18 is a left side view of FIG. 15;

FIG. 19 is a rear view of FIG. 15;

FIG. 20 is an enlarged top view of FIG. 15; and,

FIG. 21 is an enlarged bottom view of FIG. 15.

(Continued)

The broken lines rendered in FIG. 13 illustrate portions of the eyelet interference screw and form no part of the claimed design.

1 Claim, 12 Drawing Sheets
